ANIMAL-SCRATCHING DEVICE

Fred L. Heese, Pender, Nebr., assignor to Automatic Equipment Manufacturing Company, Pender, Nebr., a corporation of Nebraska

Application April 29, 1944, Serial No. 533,386

2 Claims. (Cl. 119—157)

This invention relates to animal-scratching devices of a generally similar nature to that constituting the subject matter of U. S. Patent No. 2,333,946, issued November 9, 1943, upon which the present device constitutes an improvement.

The primary object of the present invention is to provide, in a manner as hereinafter set forth, a scratching device of the aforementioned character comprising unique means, operable by the animal, for discharging powder on the body of said animal.

Other objects of the invention are to provide an improved animal-scratching device of the character described which will be comparatively simple in construction, strong, durable, highly efficient and reliable in use, compact and which may be manufactured and installed at low cost.

All of the foregoing, and still further objects and advantages of the invention, will become apparent from a study of the following specification, taken in connection with the accompanying drawings wherein like characters of reference designate corresponding parts throughout the several views, and wherein:

Figure 1 is a view in front elevation of an animal-scratching device constructed in accordance with the present invention.

Figure 2 is a view in horizontal section, taken substantially on the line 2—2 of Figure 1.

Figure 3 is a vertical sectional view through the powder dispensing means, taken substantially on the line 3—3 of Figure 1.

Referring now to the drawings in detail, it will be seen that the embodiment of the present invention which has been illustrated comprises a channel iron frame of substantially inverted U shape which is designated generally by reference character 1. The frame 1 is to be provided with suitable supporting means such, for example, as a pair of posts fixed in the ground.

Mounted for vertical sliding movement in the frame 1 is an arcuate animal-actuated brush 2. Mounted horizontally on the brush 2 is a bar 3 having its end portions slidably engaged in the legs 4 of the frame 1. A tube 5 extends vertically through the back 6 of the brush 2 and the bar 3 and is secured on the latter through the medium of angular brackets 7. In the embodiment shown, a nut 8 is threaded on the lower end portion of the tube 5 for retaining the brush 2 thereon. Upwardly diverging leaf springs 9 have their lower end portions secured on the feet 10 of the brackets 7. The upper end portions of the springs 9 are slidably engaged beneath the top member 11 of the frame

1 for yieldingly resisting upward movement of the bar 3 and the brush 2.

Mounted on the member 11 of the frame 1 is a housing 12 of substantially inverted cup shape.

5 Mounted in the housing 12 and suspended from the top 13 thereof is a collapsible, bellows-type container 14 for the reception of powder. A removable closure 15 is provided on the top 13 of the housing 12 for filling the collapsible container 14.

Suspended from the lower end of the collapsible container 14 and communicating therewith is a discharge tube 16. The discharge tube 16 extends slidably through a vertical guide bearing 17 which is provided therefor on the member 11 of the frame 1 and projects into the comparatively large tube 5. A nozzle 18 is mounted in the upper end portion of the discharge tube 16. Fixed on the discharge tube 16 at an intermediate point is a collar 19. A coil spring 20 is engaged with the collar 19 for yieldingly resisting upward movement of the discharge tube 16. A stop flange 21 on the upper end portion of the tube 16 is engageable on the member 11 of the frame 1 for limiting downward movement of said tube 16.

It is thought that the operation of the device will be readily apparent from a consideration of the foregoing. Briefly, the movable members 30 are normally held in the position shown in Figure 1 of the drawings by the springs 9 and 20 with the assistance of gravity. When an animal passes through the frame 1 the brush 2 is raised by said animal as it passes therebeneath. When 35 the brush 2, also the bar 3, are forced upwardly against the tension of the springs 9, the tube 5 engages the collar 19 and raises the discharge tube 16 against the tension of the coil spring 20. Thus, the container 14 is collapsed for ejecting a portion of the powder therefrom through the nozzle 18, said powder passing downwardly through the tubes 16 and 5 and being discharged on the body of the animal. When the animal passes from beneath the brush 2, said 45 brush returns to lowered position and the tube 16 is moved downwardly by the spring 20 for again expanding or opening the collapsible powder container 14. The device is now ready for the next operation. Downward movement of the bar 3 is limited by stops 22 on the legs 4 of the frame 1.

It is believed that the many advantages of an animal-scratching device constructed in accordance with the present invention will be 50 readily understood, and although a preferred

embodiment of said device is as illustrated and described, it is to be understood that changes in the details of construction and in the combination and arrangement of parts may be resorted to which will fall within the scope of the invention as claimed.

What is claimed is:

1. An animal-scratching device comprising a frame, an animal-actuated brush slidably mounted on said frame, a collapsible powder-dispensing container mounted on the frame, a discharge tube connected to the container, and a tube on the brush engageable with the first-named tube for collapsing the container for discharging the powder therefrom on the 15 animal.

2. An animal-scratching device comprising a substantially U-shaped frame, a housing of substantially inverted cup shape mounted on top of the frame, a collapsible powder-dispensing container mounted in the housing, a discharge tube depending from the collapsible container and extending slidably through the top portion of the frame, a collar fixed on said discharge tube, an animal-actuated brush mounted for vertical sliding movement in the frame, and a tube on the brush operable on the first-named tube and engageable with the collar for collapsing the container and discharging the powder therefrom on said animal.

FRED L. HEESE.
